ELECTRIC SWITCH

Harry C. Hall, Crystal Lake, and Horace M. Wood, Chicago, Ill., assignors to Oak Manufacturing Company, Chicago, Ill.

Application May 3, 1934, Serial No. 723,724

5 Claims. (Cl. 200—6)

This invention relates to electric switches and particularly to switches capable of operating on a large number of circuits. While the switch to be described has numerous applications, one field 5 in particular pertains to radio receivers having means for switching from one broadcast band to another band. In a receiver of this type, it is necessary that a large number of connections be made and broken. Because of the minute potentials involved, it is necessary that excellent contact be maintained at all times.

Furthermore, simplicity, compactness and cheapness are essential in a switch of this character.

15 A particularly pressing problem with such switches lies in the fact that a number of switches may be desired for operating on a certain number of circuits, while other switches may be desired for operating on a different number of circuits. Furthermore, switches of this character may have two or more positions. An important element in the cost of such switches lies in the tooling—particularly the cost of the dies to punch 20 out the contact members and other parts. Obviously, a switch having a construction flexible enough so that various changes may be made without making any change in the dies would permit of an economical manufacture of various 25 types of switches from the same tooling equipment.

An object of this invention is to devise a switch of this type whose characteristics may be varied over wide limits without any substantial change in the tooling requirements.

35 Referring to the drawing, Figure 1 is a diagrammatic view of a switch embodying this invention.

Figure 2 is a sectional elevation of the switch taken on line 2—2 of Figure 1.

40 Figure 3 is a section on line 3—3 of Figure 2.

The switch, in general, comprises a stationary member 1, of insulating material such as phenol condensate. This member is preferably 45 in the form of a flat circular plate. Mounted on member 1 in circular formation are a plurality of contacts 2, 3, 4 and the like. These contacts are preferably secured to base 1 by means of rivets 6. Each contact has an upstanding portion 7, provided with a suitable aperture 8 there- 50 in for soldering wires thereto.

Certain contacts such as 2 and 4 for example, have a bent over portion 10 provided with an active contact surface 11 above and in a plane 55 substantially parallel to that of base 1. It will be noted that contact portion 11 has its sides

bent downwardly at 12 so that the entire contact portion forms a generally curved surface with the convex portion of the curve facing outwardly.

Contact member 3 has a spring portion 16 which terminates in an upwardly extending portion 18, having a contact surface 17 perpendicular to the plane of base 1. The sides of contact portion 17 are bent at 18 and form a generally curved portion having its convex portion disposed toward the center region.

Centrally disposed of base 1 in a suitable aperture is a bushing 20 having a suitably threaded portion 21, through which passes a rotatable shaft 22. Shaft 22 preferably has its end 23 reduced and squared and carries a rotor 25 of phenol condensate or similar insulating material. This rotor is locked in place and may be maintained in position by a washer 26. This washer may be rigidly maintained on the reduced end of shaft 23 by having a shaft end peaned over. Rotor 25 carries one or more metallic contact members 30 having any desired angular extent. As shown in the drawing, there are three contact members of equal size covering the 330 degrees.

Movable contact members 30 are rigidly joined 25 to rotor 25 by means of rivets 31. The inside surface of contact member 30 may be formed smoothly circular as at 33. The outer surface is preferably formed so that a plurality of slots 35 are provided. These slots are preferably so disposed with regard to their angular extent and position as to correspond in number with the stationary contacts 2 to 4 inclusive. While ordinarily most of the slots 35 are formed by cutting away or punching out the metal filling these 35 slots, certain of the slots such as slot 36 may be formed by bending the metal 37 downwardly to form a tongue. This tongue has its outer surface preferably smoothed off and curved at 38 and depends downwardly to make contact with 40 the contact portion 11 of the stationary contact members.

It will be noted that rotation of rotor 25 will cause the fixed contact tongues 11 to remain in contact at all times with movable contact 30. 45 Such a connection may form a ground or any common circuit connection, as desired. Depending tongue 37 from movable contact member 30 may ride over from one stationary contact to another, as desired, and change the circuit connections in any manner desired.

It will be noted that by virtue of the cooperating curvature of tongue 11 and slot 35 that the rotor will be maintained in any one of a plurality of stable positions. In this way any one 55

of a number of definite switching positions may be established. In order to provide stops between which the rotor may operate, insulating member 25 is preferably provided with a plurality of apertures 40. Into any one or more of such apertures pins 41 may be disposed. These pins depend from member 25 downwardly toward base 1 and are adapted to cooperate with a fixed stop 42. This stop is formed from a sheet metal member having a washer portion 43 and a locking portion 44. This latter locking portion is adapted to fit into a corresponding slot in base 1 and anchors stop 42 against rotation. In order to maintain the rotor tightly in position a cotter pin 50 may be disposed through shaft 22 and bear against bushing 21.

In operation, rotor 25 may be turned between the limits set by the location of pins 41, operating in conjunction with stop 42.

By disposing the two types of fixed contacts, that is contacts 2 or 3, in desired position, in conjunction with adjusting the angular extent of each of movable contact members 30, a large number of different switching actions may be obtained.

In addition, depending contact member 31 from movable contact 30 may be chosen from a larger number of positions or may be entirely omitted if desired.

Obviously, in the manufacture of contact member 30 the die for punching out this member preferably has portions removable at will for forming slots 35. Hence, if any tongues 37 are to be retained, the die may be adjusted accordingly. It is clear, therefore, that by means of this construction the original equipment such as the dies for forming the fixed and movable contacts and the various insulating pieces need not be changed in any substantial manner for changing the characteristics of the switch.

What we claim is:

1. An electric switch comprising a stationary and rotary member, a series of contacts carried by each of said members, one of said series having a larger number of contacts than the other series, each contact of the second series having an extended contact area and being adapted to cooperate with a plurality of the contacts of the first series, one of the contacts of said first series being in contact at all times with the extended contact of said second series, said extended contact having a serrated active surface, each serration defining an index position for said rotatable member and at least one member integral with said contact, depending therefrom and bent to form a serration for cooperating with the contacts of said first series.

2. An electric switch comprising a stationary member having a series of fixed contacts circularly arranged thereon, a rotatable member carrying a series of contacts and adapted to cooperate with said fixed contacts, said rotatable contacts each being formed as a member having an extended contact surface having an angular extent equal to at least two of said stationary contacts, each rotatable contact having a ser-

rated edge, at least one of said stationary contacts cooperating with said movable contact having a spring portion cooperating with said serrated edge and adapted to lock said rotating contact in one of a plurality of positions, and a contact portion integral with said one movable contact and bent to form a serration, said contact portion being adapted to cooperate with certain of said fixed contacts.

3. An electric switch comprising a stationary member having a series of fixed spring contacts mounted thereon, a rotatable member carrying at least one movable contact for cooperating with said stationary contacts, said movable contact having its outer edge provided with a series of regularly spaced slots, one of said fixed contacts having a spring tongue adapted to press against the edge of said movable contact at all times and to fit into each slot for determining a position of rest, said movable contact member having a portion thereof bent to form one of said slots, said portion functioning as a movable contact tongue for cooperation with certain fixed contacts.

4. An electric switch comprising a stationary member having a series of fixed spring contacts circularly disposed therein, each of said spring contacts having a contacting tongue, a rotor mounted on said stationary member and carrying at least one movable contact member, said movable contact member having an active outer edge, said outer edge having a series of slots formed therein, one of said stationary contacts having a tongue adapted to press against said movable contact at the outer edge thereof and having a curved surface for cooperation with said slots to define a plurality of stable rotor positions, said movable contact having a contact tongue formed from the material in one of such slots, said contact tongue being bent away from the plane of said movable contact and adapted to cooperate with fixed contacts.

5. An electric switch comprising a stationary member having a plurality of contacts mounted thereon and disposed in circular formation, certain of said contacts having upstanding active portions and other contacts having active portions bent over to said stationary member, a rotor carried by said stationary member, said rotor having a plurality of movable contact members, each movable contact member having an angular extent equal to at least two stationary contacts and having an outer edge provided with slots corresponding in number and position to the stationary contacts, the upstanding portions of certain said stationary contacts being adapted to press against the edge of said movable contact at all times and define a plurality of stable rotor positions when said upstanding portion of said stationary contact springs into a slot and a tongue integral with one of said movable contact members and bent away to form a slot, said tongue cooperating with the stationary contacts having the parallel contact portions.
